UNITED STATES PATENT OFFICE.

GEORGE W. BIRD, OF PITTSBURGH, PENNSYLVANIA.

RAILWAY CAR.

Application filed October 14, 1921. Serial No. 507,746.

To all whom it may concern:

Be it known that I, GEORGE W. BIRD, a citizen of the United States, residing at 37 Ruth Street, Pittsburgh, in the county 5 of Allegheny and State of Pennsylvania, have invented a new and useful Improvement in Railway Cars, of which the following is a specification.

My invention relates to railway-cars.

- 10 The object of my invention is to provide a railway-car of such construction that when two or more cars are coupled together, as in the case of a trailer, the cars may be brought so close together that the passengers 15 may pass conveniently and without danger from one car to the other by means of the intervening platforms or vestibules, thereby making it possible to handle with one crew the passengers in both cars.
- 20 A further object of my invention is to provide for enclosing the passage from one car to the other so as to guard against rain and snow, and at the same time providing for the movement of the cars on curves and 25 on grades without interfering in any way with said protecting means.

In the accompanying drawing Fig. 1 is a side elevation of a portion of two cars embodying my invention connected together; 30 Fig. 2 is a plan view of same; Fig. 3 is a plan view showing the cars going around a curve; Fig. 4 is a horizontal sectional view; Figs. 5 and 6 are enlarged details of the protecting curtain.

35 In the accompanying drawings the numeral 2 designates a portion of a railway-car of a construction provided at one end with the rounded buffer-sills 3, the end-portion 4 sloping upwardly and inwardly from said 40 sill to the roof 5. By this construction the two cars, when coupled up by a coupler bar 6, may have their sills 3 in very close relation, in fact, as little as an inch or two, so that passengers may pass from one car to 45 the other without inconvenience or danger, and by having the inwardly sloping end portions the distance between the cars gradually increases toward the top so that when the cars reach a dip in the track where one car 50 is on the ascent and the other on the decline of said dip there will be sufficient room to allow for the upper ends of the cars to approach each other without interference.

To protect the space between the cars 55 as against the entrance of rain and snow, the guards 7 are provided which may be

formed of canvas or any other suitable material. Each guard is mounted on a frame comprising the rods 8 and 9 connected by the cross-rods 10, the cross-rods being hinged as 60 at 11 to the rod 8 secured to the car. The uppermost of the connecting rods 10 is provided with the branch portion 12, at the inner end of which is mounted the roller 13. A roller 14 is mounted at the outer end of 65 said branch and, as illustrated in Fig. 2, under normal conditions the roller 14 engages the curve 15 at the upper portion of the car. A spring 16 is connected to the uppermost connecting rod 10 and to the car at 70 17, said spring acting to hold the guard-frames normally in the position shown in Fig. 2. If, however, the cars are moving around a curve the guard-frames assume the position shown in Fig. 3, the rollers 13 on one 75 side engaging the curved portion of the car while the rollers 14 on that side are out of contact with the car, and if the cars are in a dip, as above described, and the upper portions 5 to move toward each other it will be 80 apparent that the curtain frames will move in opposite directions or spread apart, so that the rollers 13 will both come in engagement with the curved portion 15, and when the cars assume a normal position the 85 springs 16 will return the guard frames to their regular positions.

Sliding doors 18 are provided to move back and forth in the frames 19.

A cover is provided for the space between 90 the cars by the employment of the hinged plates 20, said plates mounted on rods 21 so as to swing freely thereon, and when two cars are joined together these plates overlap and shed rain, arranged at an angle for 95 this purpose. It will be apparent that when the cars are in a dip the plates move one over the other as the upper ends of the cars approach each other, and on the sharpest curve portions of the plates will still overlap each 100 other.

What I claim is:

1. A railway-car having its rear face sloping inwardly from the buffer-sill to the roof.
2. A railway car having its rear face 105 sloping inwardly from the buffer sill to the roof, and a single swinging frame at the end thereof, said frame tapering from the top to the bottom, and a shield or cover carried by said frame.
3. In a railway-car, the combination of 110 single swinging frames mounted at the ends

thereof, shields or coverings for said frames, and springs connected to said frames and to the car for holding said frames normally in parallel relation whereby said shields are adapted to close the space between adjoining cars.

4. In a railway-car, the combination of swinging frames mounted at the end thereof, normally held in parallel relation to each other, shields or coverings for said frames, and rollers at the upper ends of said frames adapted to engage the curved end portion of an adjoining car.

5. In a railway-car, the combination of

swinging end frames mounted at the end thereof normally held in parallel relation to each other, a shield or covering for said frames, a branch at the upper end of each said frame carrying a roller at each end thereof adapted to engage the curved end portions of the adjoining car.

6. In a railway-car, an upwardly inclined swinging cover piece mounted at the end thereof, projecting beyond the roof of the car, and means for maintaining said cover piece in inclined position.

GEORGE W. BIRD.
